UNITED STATES PATENT OFFICE.

DANIEL W. CAMPBELL AND ALBERT E. PRESCOTT, OF NORTH CREEK,
NEW YORK.

WATCHCASE-OPENER.

SPECIFICATION forming part of Letters Patent No. 659,049, dated October 2, 1900.

Application filed November 17, 1899. Serial No. 737,344. (No model.)

To all whom it may concern:

Be it known that we, DANIEL W. CAMPBELL and ALBERT E. PRESCOTT, citizens of the United States, and residents of North Creek, in the county of Warren and State of New York, have invented certain new and useful Improvements in Watchcase-Openers; and we do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a representation of a perspective view illustrating the invention. Fig. 2 is a vertical central section.

The invention has relation to means for opening the screw-cases of watches and others having polished or otherwise finely-finished exterior surfaces; and it consists in the novel construction and combination of parts, as hereinafter set forth.

The case of a watch has its front and back fitted to engage the body in the nicest manner, and it is not easy to unscrew the parts without injuring the finely-finished surface.

The object of this invention is to provide an instrument whereby the back or front can be readily unscrewed without marring the surface of the case.

In the accompanying drawings the letter A designates the body of the instrument, which is preferably made of wood, its end portions being cylindrical, as indicated at b. Between the end portions the body is narrowed in waist form, being annularly grooved, as indicated at c. The fillets d d, forming the sides of this groove, are slightly concave and join the cylindrical portions at an obtuse angle e, designed to fit the finger-joints in grouping the end portion of the instrument in such a manner that a secure grip can be obtained. The ends of the body portions b are round and concave, as indicated at g, and as the instrument is preferably made double—that is to say, having each end adapted to engage the case—the concavities are made of different radial curvature, one be-

ing of flatter contour than the other. In this manner the instrument is designed to be applied to cases of different convex contours. Each end of the instrument is provided with a concave facing f, of rubber of about one-tenth of an inch in thickness, which is firmly cemented to the concave end of the body. The outer margin m of the edge of the rubber facing presents beyond the plane of the end of the body portion and serves by its projection to prevent any harsh contact of the body portion of the instrument with the finished surface of the watch when applied thereto. The instrument being a sort of soft-faced wrench is applied by pressing the rubber-faced concave end against the convex surface of the watchcase back or front, when it will be found to engage the surface in a sufficiently intimate manner to serve efficiently in unscrewing the part without injury to its interior finish.

It is apparent that the instrument may be made single or double; but the latter is the preferred form, as the rubber facing assists the grip in operating the instrument.

It will be noted that in a wrench of this character, intended to operate upon delicate polished surfaces, a yielding facing must be provided for contact with such surfaces in order to avoid crushing or scratching the same. This yielding facing will also largely assist the grip of the wrench, for the reason that it will exclude the air, as the said facing will adapt itself to any irregularities.

Having described the invention, what we claim, and desire to secure by Letters Patent, is—

1. A wrench for opening watchcases consisting of an unyielding body provided with a handle, and having a concave end, and a concave facing of soft rubber immovably secured upon said end, substantially as specified.

2. A case-opener, having a cylindrical end portion terminating in a concave end lined with a concave rubber facing having its margin projecting beyond the level of said concave end, substantially as specified.

3. A case-opener, consisting of the body having the cylindrical end portions, the an-

nular gripping-groove between said end portions, the concave ends of different curvature, and the rubber facings of said concave ends, substantially as specified.

5 4. A tool for the purpose described, consisting of an unyielding body provided with a handle, and having a concave end, and a concave soft-rubber facing immovably secured upon said end and having its margin

projecting beyond the level thereof, substantially as specified.

In testimony whereof we affix our signatures in presence of two witnesses.

DANIEL W. CAMPBELL.
ALBERT E. PRESCOTT.
